his Attorney.

UNITED STATES PATENT OFFICE.

JOHN C. CAMPBELL, OF CHICAGO, ILLINOIS.

METAL CAR-ROOF.

No. 809,907.

Specification of Letters Patent.

Patented Jan. 9, 1906.

Application filed May 16, 1904. Serial No. 208,149.

To all whom it may concern:

Be it known that I, JOHN C. CAMPBELL, a citizen of the United States, and a resident of Chicago, in the county of Cook and State of Illinois, have invented certain new and useful 5 Improvements in Metal Car-Roofs, of which the following is a full, clear, and exact description.

The present invention has relation more 10 particularly to that class of car-roofs generally known as "outside" metal roofs; and the invention consists in the features of improvement hereinafter described, illustrated in the accompanying drawings, and more 15 particularly pointed out in the claims at the end of this specification.

In the construction of outside metal car-roofs it has been the common practice to 20 bend downwardly the outside edges or eave portions of the metal sheets that comprise the roof and to secure these downwardly-bent edges by means of nails. A serious objection to such construction is that in practice it is found that the metal sheets crack or 25 break adjacent the eaves, this cracking or breaking of the sheets being due partly to the expansion and contraction of the metal under variations of temperature, but more especially to the great strains thrown upon the 30 sheets incident to the violent service to which the cars are subjected.

My present invention has for its object to 35 provide an outside metal car-roof the sheets of which are so joined together and to the body of the car that they shall yield sufficiently to compensate for the expansion and contraction of the metal and to allow also for the racking strains to which the car is subjected in service.

40 Figure 1 is a perspective view of a portion of the car-roof to which my improved outer metal roof is applied, certain of the parts being shown in section. Fig. 2 is a detail perspective view of one of the transverse sections of the improved metal roof. Fig. 3 is a 45 detail section through the ridge-pole and center of the car-roof. Fig. 4 is a detail section showing an inner face view of the depending end flanges of the transverse metal roof sections, and Fig. 5 is a detail perspective view of the retaining-strip for the improved metal roof.

A designates the body of the car, that may be provided with the wooden roof-boards B 55 in the usual manner, these roof-boards being sustained by the ridge-pole C, the carlines D,

the purline-strips E, and the outer purline-strips F, as will be readily understood by those familiar with freight-car construction. My improved roof is formed of a series of galvanized-iron roof-sheets G, that extend transversely of the car. One edge of each of the sheets G is formed with an upturned flange g and the other edge of each sheet is formed with a U-shaped flange g'. When the sheets 60 are set together in position upon the roof, the straight flange g of one sheet will extend within the folds of the U-shaped flange g' of the next adjacent strip, as clearly shown in Fig. 4 of the drawings. At the center the 70 edges of the strips are cut away, as at g², and are preferably provided with the upwardly-extending semicircular flanges g³, these flanges g³ being of sufficient height to prevent 75 water passing down through the holes formed by the cut-away spaces g². The ends of each strip are bent downwardly and reverted to form the U-shaped flanges g⁴, that extend along the eaves of the car-roof, as clearly shown in Fig. 1 of the drawings. The 80 inner folds or sections g⁵ of each of the U-shaped flanges g⁴ is shorter than the outer folds, and when the strips are set together to form the roof, as shown in Fig. 1 of the drawings, the edges of the folds or sections g⁵ abut 85 or approximate each other. The U-shaped flanges g⁴ are formed at their opposite ends with the overlapping or extending portions g⁶ and g⁷, the underlying projecting portions g⁸ being preferably longer than the portions g⁷. 90

In forming my improved roof the sheets G will be set together with their flanges g and g' interlocking, as shown, and with the lapping portions or extensions g⁶ sitting beneath the extensions g⁷, as indicated in dotted and full lines in Figs. 1 and 4 of the drawings. Saddle-blocks H, which carry running-boards H', will then be set over the interlocked flanges g and g' of the sheets in manner well understood, these saddle-blocks H being formed with longitudinal grooves to receive the flanges of the sheets. Each of the saddle-blocks H is formed with a bolt-hole, through which will pass a bolt K, that passes downward through the cut-away spaces g² of 105 the sheets and through the roof-boards and ridge-pole C, the inner end of the bolt K being furnished with a retaining-nut k. As the sheets G are thus set together retaining plates or strips M will be slipped edgewise between 110 the eave-flanges g⁴ of the strips and the side-walls of the car, and these retaining plates

or strips M are formed each with a downwardly-turned flange m, that will interlock with the inner section g³ of the eave-flanges g⁴. The lower portions of the retaining plates 5 or strips M extend below the eave-flanges g⁴ of the roof-sheets and are securely fastened to the car by nails P, as shown in the drawings.

From the foregoing description it will be seen that the sheets G are not nailed to the car-body, but are securely held in place upon the roof-boards by reason of the interlocking of the eave-flanges g⁴ of the roof-sheets with the reverted flanges m of the retaining plates or strips M. Preferably the flanges g⁴ of the outer ends of the sheets will be of sufficient width and sufficiently open not only to allow for readily setting the retaining plates or strips M in position, but also to allow for the contraction and expansion of the metal of the roof-sheets and to allow also sufficient yielding of the metal at such points to compensate for the strains upon the sheets incident to the violent service to which the car is subjected. The retaining plates or strips M may be of 15 any suitable length; but preferably these plates or strips are about equal in length to the width of the roof-sheets G and are arranged to break joints with the sheets, as indicated in the drawings.

Not only does my invention afford a most effective means for holding the car-roof in position upon the car, but it will be seen that the construction of the parts is such as to most effectively prevent the access of water 30 around the eaves of the roof or at the joints of the roof-sheets.

Having thus described my invention, what I claim as new, and desire to secure by Letters Patent, is—

1. A car-roof comprising roof-sheets having their ends formed with reverted eave-flanges, the eaves portion of one at least of said sheets being provided with a laterally-extending portion overlapping the joint between adjoining sheets, and retaining-plates engaging the 45 reverted eave-flanges of the roof-sheets.

2. A car-roof comprising roof-sheets having their ends formed with downwardly-extending U-shaped eave-flanges, the inner portions of said eave-flanges being shorter than the outer portions thereof, said outer portions being arranged to overlap, and retaining plates or strips engaging the U-shaped eave-flanges of said roof-sheets.

3. A car-roof comprising roof-sheets having 55 their edges formed with interlocking flanges and having their ends formed with U-shaped eave-flanges, the inner portions of said eave-flanges being arranged to abut and the outer portions of said eave-flanges being arranged 60 to overlap, in combination with retaining plates or strips having flanges interlocking with the eave-flanges of the roof-sheets.

4. A metal car-roof comprising roof-sheets extending transversely of the car and having 65 flanged interlocking edges, the edges of the sheets being formed at their centers with cut-away spaces and with upturned flanges about said spaces in combination with saddle-blocks and retaining-bolts for holding said sheets in 70 position.

5. A car-roof, comprising metal sheets extending transversely of the car and having their outer ends reverted to form U-shaped bends at the eaves of the roof, in combination 75 with metal retaining-plates secured to the car and extending lengthwise thereof, the free edges of said retaining-plates being rebent to form flanges that set within the U-shaped eave-flanges of the roof-sheets, the said U-shaped flanges of the roof-sheets and the rebent flanges of the retaining-plates being spaced both laterally and edgewise of the latter to permit universal play between the roof-sheets and the car, said roof-sheets being unsecured to the car-roof other than substantially at the ridge, by said flanges, and at the 80 ends of the car.

Correction in Letters Patent No. 809,907.

It is hereby certified that Letters Patent No. 809,907, granted January 9, 1906, upon the application of John C. Campbell, of Chicago, Illinois, for an improvement in "Metal Car-Roofs," were erroneously issued to "said Campbell" as owner of the entire interest in said invention; that said Letters Patent should have been issued to the inventor *John C. Campbell and John H. Allen of Chicago, Illinois, jointly*, said John H. Allen being assignee of one-third interest in said patent, as shown by the record of assignment in this office; and that the said Letters Patent should be read with this correction therein that the same may conform to the record of the case in the Patent Office.

Signed and sealed this 30th day of January, A. D., 1906.

F. I. ALLEN,
Commissioner of Patents.

or strips M are formed each with a downwardly-turned flange m, that will interlock with the inner section g³ of the eave-flanges g⁴. The lower portions of the retaining plates 5 or strips M extend below the eave-flanges g⁴ of the roof-sheets and are securely fastened to the car by nails P, as shown in the drawings.

From the foregoing description it will be seen that the sheets G are not nailed to the car-body, but are securely held in place upon the roof-boards by reason of the interlocking of the eave-flanges g⁴ of the roof-sheets with the reverted flanges m of the retaining plates or strips M. Preferably the flanges g⁴ of the outer ends of the sheets will be of sufficient width and sufficiently open not only to allow for readily setting the retaining plates or strips M in position, but also to allow for the contraction and expansion of the metal of the 15 roof-sheets and to allow also sufficient yielding of the metal at such points to compensate for the strains upon the sheets incident to the violent service to which the car is subjected. The retaining plates or strips M may be of 20 any suitable length; but preferably these plates or strips are about equal in length to the width of the roof-sheets G and are arranged to break joints with the sheets, as indicated in the drawings.

30 Not only does my invention afford a most effective means for holding the car-roof in position upon the car, but it will be seen that the construction of the parts is such as to most effectively prevent the access of water 35 around the eaves of the roof or at the joints of the roof-sheets.

Having thus described my invention, what I claim as new, and desire to secure by Letters Patent, is—

40 1. A car-roof comprising roof-sheets having their ends formed with reverted eave-flanges, the eaves portion of one at least of said sheets being provided with a laterally-extending portion overlapping the joint between adjoining sheets, and retaining-plates engaging the 45 reverted eave-flanges of the roof-sheets.

2. A car-roof comprising roof-sheets having their ends formed with downwardly-extending U-shaped eave-flanges, the inner portions of said eave-flanges being shorter than the outer portions thereof, said outer portions being arranged to overlap, and retaining plates or strips engaging the U-shaped eave-flanges of said roof-sheets.

3. A car-roof comprising roof-sheets having 55 their edges formed with interlocking flanges and having their ends formed with U-shaped eave-flanges, the inner portions of said eave-flanges being arranged to abut and the outer portions of said eave-flanges being arranged 60 to overlap, in combination with retaining plates or strips having flanges interlocking with the eave-flanges of the roof-sheets.

4. A metal car-roof comprising roof-sheets 65 extending transversely of the car and having flanged interlocking edges, the edges of the sheets being formed at their centers with cut-away spaces and with upturned flanges about said spaces in combination with saddle-blocks and retaining-bolts for holding said sheets in 70 position.

5. A car-roof, comprising metal sheets extending transversely of the car and having their outer ends reverted to form U-shaped bends at the eaves of the roof, in combination 75 with metal retaining-plates secured to the car and extending lengthwise thereof, the free edges of said retaining-plates being rebent to form flanges that set within the U-shaped eave-flanges of the roof-sheets, the said U-shaped flanges of the roof-sheets and the rebent flanges of the retaining-plates being spaced both laterally and edgewise of the latter to permit universal play between the roof-sheets and the car, said roof-sheets being un- 85 secured to the car-roof other than substantially at the ridge, by said flanges, and at the ends of the car.
